TRAVELING WAVE TUBE SLOW WAVE STRUCTURE HAVING BI-FILAR HELICES

Frank E. Vaccaro, New Brunswick, N.J., assignor to the United States of America as represented by the Secretary of the Air Force

Filed June 23, 1961, Ser. No. 119,774
5 Claims. (Cl. 315—3.6)

This invention, in general, relates to improvements in helical wire transmission lines as used in beam traveling wave tubes and, more particularly, to novel means for suppressing backward wave oscillation in traveling wave tube amplifiers that employ bifilar helices.

Traveling wave tubes usually employ a long, thin cylindrical electron beam that must be confined continuously throughout its length by electric and/or magnetic forces. The common method of overcoming the diverging space-charge forces in a high density stream of electrons is to use an axial magnetic field, either uniform or alternating, along the axis of the beam. By using a series of small ceramic permanent magnets to provide a periodic magnetic field on the axis of the beam, the weight and focusing power required can be reduced substantially below that necessary for uniform magnetic fields. However, much of the bulk and weight in a packaged traveling wave tube of this type is still due to the magnets. The use of electrostatic forces to focus the electron beam in a traveling wave tube eliminates the need for magnet structure, considerably reduces the weight of the packaged tube and also eliminates the problem of alignment of the tube within the magnetic field. Because the helix used in conventional traveling wave tubes is a relatively simple structure that makes possible transmission of R-F energy over extremely wide bandwidths, an electrostatic focusing method utilizing such a structure is highly desirable. Certain traveling wave tube amplifiers known in the art provide electrostatic focusing means, wherein the basic R-F properties of the helix are preserved, by interwinding two helices in a bifilar manner. The electrostatic focusing action in such a device is obtained by operating the two helices at different potentials.

Electrostatically focused traveling wave amplifiers employing bifilar helices are, however, subject to the same unwanted backward wave oscillations as are unifilar amplifiers. This condition occurs because both types of amplifier have circuits that will support backward wave modes. These modes are characterized by the fact that the phase and group velocity of the wave are opposite in direction. In general traveling wave interaction occurs when an electron beam has a velocity that is approximately equal to the phase velocity of the wave. It is also well known that energy propagates along a circuit in the same direction as the wave group velocity. The fact that backward waves have group and phase velocity opposite in direction provide inherent feedback mechanism and oscillations will build up in these modes when the interaction between the beam and the fields associated with these modes are of sufficient strength to overcome the losses in the loop.

Accordingly, it is a principal object of my invention to provide, in a traveling wave tube amplifier, a novel bifilar helical slow wave structure adapted to suppress oscillations resulting from beam interaction with the antisymmetric backward wave mode.

It is another object of my invention to provide an electrostatically focused traveling wave tube amplifier including a bifilar helical slow wave structure, said slow wave structure having a geometric configuration especially adapted to suppress backward wave oscillations.

Still another object of my invention is to provide an electrostatically focused traveling wave tube amplifier hav-

2

ing two-helical slow wave structures interwound in a bifilar arrangement, each of said slow wave structures being fabricated from a different size wire and having different electrical potentials impressed thereon.

The novel features which are believed to be characteristic of the invention, both as to its organization and method of operation, together with further objects and advantages thereof, will be better understood from the following description considered in connection with the accompanying drawings in which one presently preferred embodiment of my invention is illustrated by way of example. It is to be expressly understood, however, that the drawings, are for the purpose of illustration and description only, and are not intended as a definition of the limits of the invention.

In the drawings:

FIGURE 1 illustrates a traveling-wave tube amplifier of the type comprehended by my invention;

FIGURE 2 is a sectional view of said traveling-wave tube taken at A—A;

FIGURE 3 illustrates the symmetric forward wave field configuration of a conventional bifilar helix;

FIGURE 4 illustrates the antisymmetric backward wave field configuration of a conventional bifilar helix; and

FIGURE 5 illustrates the antisymmetric backward wave field configuration associated with the novel structure of my invention.

It is the usual practice to operate traveling wave-tube amplifiers that employ bifilar helices in the symmetric forward wave ($m=0$) mode. This mode exhibits the R-F field configuration illustrated in FIGURE 3. The beam interaction and the field configurations for this mode are essentially the same as the $m=0$ mode in the case of the unifilar helix, with the exception that the impedance of the circuit has been increased by the addition of the second helix. This bifilar arrangement, however, also allows the existence of an antisymmetric backward wave mode that can interact with the electron beam and cause the tube to oscillate at low values of beam current. The R-F electric field distribution along the bifilar helix for the case of the antisymmetric backward wave mode is illustrated by FIG. 4. In this mode of operation the two helices act similar to a two-wire transmission line in the TEM mode, and either the symmetric or antisymmetric mode can exist independently. Suppression of the antisymmetric mode, therefore, will not adversely affect the overall tube gain or efficiency.

Since the electron beam can interact with the fields of the backward-wave antisymmetric mode and cause the tube to oscillate, it is the primary object of my invention to provide a tube of the type described having a bifilar helix structure, the unique geometric configuration of which is particularly adapted to suppress said antisymmetric mode. I propose, therefore, a slow wave structure comprising two helically wound wire transmission lines interwound in a bifilar manner. I further propose that one of said slow wave structures be fabricated from wire of substantially larger diameter than the other said structure. FIGURE 1 illustrates such an arrangement wherein slow wave structure 13 is interwound with slow wave structure 12. The relative wire sizes are illustrated by d_4 and d_3 in FIGURE 2. With respect to the wire sizes, it is well known that if a wire is very small there will be much electric and magnetic energy very close to the wire which is not associated with the desired field component. Also, if a wire is very large the internal diameter of the helix becomes considerably less than the mean diameter, and the space available for electron flow is reduced. Therefore, in the present invention, wire diameters d_3 and d_4 are designed to be as large and as small, respectively, as is compatible with frequency and circuit parameters.

From an examination of FIGURES 2 and 5, it is obvious that, for the purpose of antisymmetric backward wave-mode suppression, mean diameter d_1 of helix 12 should be small compared to mean diameter d_2 of helix 13. This will suppress beam interaction with the backward-wave mode since, due to the difference in mean diameters, the fields of the antisymmetric backward wave mode have a component directed away from the beam and are partially shielded from it by the larger diameter helix.

Additional suppression of the antisymmetric backward wave mode is achieved by coating small wire helix 13 with some lossy substance such as aquadag. While this will further attenuate the antisymmetric mode and prevent oscillation from building up in the mode, it will also incur some loss in the symmetric mode. This loss in the symmetric mode can be kept to a minimum, however, by proper excitation and by optimizing the loss of small wire helix 13.

The making of one helix of a smaller wire and a larger mean diameter necessitates that said helix be operated at a different potential than would be required for the same focusing characteristics obtained when both helices are of the same size wire. This is an additional advantage of my invention, in the case of electrostatic focusing, if the potential is made to correspond to the potential that exists on one of the electron gun electrodes.

Referring now to FIGURE 1 there is illustrated a traveling-wave tube amplifier employing the principles of my invention. The traveling-wave tube thus illustrated comprises electron gun 20 and collector electrode 15 at the respective ends of tubular vacuum envelope 11. Cooling fins 16 of collector electrode 15 provide rapid heat dissipation. Electron gun 20 is of conventional design and includes a heater, an emissive cathode button, a focusing electrode, and heater supply 22. Accelerator electrode 21 is arranged to direct a beam of electrons along the axis of the tube to collector 15. Large wire conductive helix 12 is supported longitudinally within vacuum envelope 11 by ceramic dowels 14. Ceramic dowels 14 have lossy coatings 17 disposed thereon for the purpose of attenuating reflected energy of the forward mode, said lossy coatings 17 being arranged in such a manner as to preclude any possible partial short-circuit between helix turns. Helix 12 is terminated at its end nearer the cathode electrode by an arrangement for coupling to input waveguide 18, and its end nearer the collector electrode by an arrangement for coupling to output waveguide 19. In the present example, this is effected by providing the helix with extensions 27 and 28, respectively, said extensions being proximate to said input and output waveguides. Small wire conductive helix 13 is interwound with helix 12 and is insulated therefrom. Helix 13 is supported by dowels 14 in the same manner as helix 12, and is made lossy over its entire length. A power supply source, such as battery 23, is connected to provide suitable operating potentials for the various tube elements. Helix 13 is made to operate at the same potential as cathode electrode 20, and a voltage difference between helix 13 and helix 12 of 2000 v. is maintained.

Although the present invention has been described with particular reference to a certain specific embodiment, it will be understood that the invention is capable of still other forms of physical expression, and consequently is not limited to the specific disclosure, but only by the scope of the appended claims.

I claim:

1. In a traveling wave amplifier tube, a slow wave structure comprising first and second wire helices arranged in a bifilar relationship, said first helix being fabricated of smaller diameter wire than said second helix, and a plurality of dielectric rods disposed externally adjacent to both said wire helices, and parallel to the common axis thereof, for the purpose of supporting said slow wave structure.
2. In a traveling wave amplifier tube having a cathode and an anode, a slow wave structure comprising, in combination, first and second helical wire transmission lines, each of said transmission lines being electrically isolated and interwoven on a common longitudinal axis in a bifilar arrangement, said first transmission line being maintained at cathode potential, said second transmission line being maintained at a higher electrical potential and fabricated of substantially larger diameter wire than said first transmission line, and a plurality of dielectric rods disposed externally adjacent to said transmission lines and parallel to the axis thereof for the purpose of supporting said slow wave structure in axial alignment.
3. In a traveling wave tube amplifier a slow wave structure comprising first and second conductive wire helices, said first helix being fabricated from substantially smaller diameter wire than said second helix and said first and second helices being interwound about a common longitudinal axis in alternating contiguous turns, said turns being of equal outside diameter and having electrical isolation therebetween, and a plurality of dielectric rods disposed externally adjacent to both said wire helices, and parallel to the common axis thereof, for the purpose of supporting said slow wave structure.
4. A slow wave structure as set forth in claim 3 wherein in said first helix is of relatively high loss.
5. A traveling wave amplifier tube comprising a slow wave structure having input and output means and consisting of first and second conductive wire helices, said first helix being fabricated from substantially smaller diameter wire than said second helix and said first and second helices being interwound about a common longitudinal axis in alternating contiguous turns, said turns being of equal outside diameter and having electrical isolation therebetween, a rigid envelope comprising a series of parallel supporting rods and a straight cylindrical portion surrounding said slow wave structure coaxially and spaced radially therefrom, means to impress high frequency waves to be amplified upon said slow wave structure input means, an electron gun positioned to project a beam of electrons along said slow wave structure in energy exchanging relationship with the high frequency waves traveling thereon, a direct current source connected to said electron gun and to said helices, and adjusted to provide beam velocity and focusing compatible with said slow wave structure and the high frequency waves traveling thereon, and means for deriving said high frequency waves in amplified form from said output means of said slow wave structure.
